his Attorney.

UNITED STATES PATENT OFFICE.

AMBROSE C. STOUDER, OF MUNCIE, INDIANA.

STABBING ATTACHMENT FOR PAPER-CUTTING MACHINES.

SPECIFICATION forming part of Letters Patent No. 433,496, dated August 5, 1890.

Application filed October 2, 1889. Serial No. 325,809. (No model.)

To all whom it may concern:

Be it known that I, AMBROSE C. STOUDER, a citizen of the United States, residing at Muncie, in the county of Delaware and State of Indiana, have invented certain new and useful Improvements in Stabbing Attachments for Paper-Cutting Machines; and I do hereby declare the following to be a full, clear, and exact description of the invention, such as will enable others skilled in the art to which it appertains to make and use the same.

My invention relates to an improved stabbing attachment for paper-cutting machines; and it consists of a detachable and adjustable stabber adapted to be secured to the clamp of the cutter. The particular construction and arrangement of the various parts of the same and the means employed for securing the same to the clamp I will now proceed to point out and describe, reference being had to the accompanying drawings, in which—

Figure 1 is a perspective of the clamp of a paper-cutter provided with my invention, the cutter being removed. Fig. 2 is a vertical section of the same; Fig. 3, a perspective of the stabber removed from the clamp, showing the under side of the same; Fig. 4, a detail in perspective showing one of the adjustable blocks carrying the stabbing-needle; Fig. 5, a detail illustrating a modified form of the adjustable block.

Referring to said drawings, A represents the bed of a paper-cutting machine. Secured to said bed is a frame of ordinary construction, in which is mounted a paper-clamp C, provided with the usual operating-screw D. The rear side of said clamp is provided with a longitudinal flange e, to which the stabber is attached, as hereinafter described.

E is a flat bar having a longitudinal recess e on its under side, said recess having inwardly-beveled sides.

F is an upwardly-curved arm, secured to the center of the bar E and extending up over the top of said bar.

f is a set-screw mounted in the upper end of the arm F over the bar E. The lower end of the arm extends across the center of the recess in the bar and has secured to its under

side one of the stabbing-needles G. On each side of the arm or fixed needle I mount in the

recess e adjustable blocks H, having beveled ends which engage with the beveled sides of the recess, and are thus held therein. One of the beveled ends h of said blocks is detachable, and is provided with pins h', which enter holes h² in the main block, and are also provided with a spring h³, interposed between said detachable end and the main block, thus forming a spring end, which causes the beveled edges of the blocks to bind against the beveled sides of the recess and hold the blocks at the desired point of adjustment. To each of said blocks is secured a stabbing-needle G, similar in form to the central fixed needle. Instead of using the spring ends for the blocks, said blocks may be made solid, and arranged to fit accurately in the recess and be held as adjusted simply by frictional contact.

The stabber is attached to the clamp by placing the bar on the under side of said clamp at the desired point and screwing the set-screw down until it engages with the flange on said clamp, as shown in Figs. 1 and 2. The stabbing-needles, it will be seen, can be adjusted to or from the center of the bar. Immediately under the stabbing-needles a transverse slot or recess I may be formed in the bed to permit said needles to pass through and allow the clamp to engage the paper.

I have not shown or described the cutter used with the clamp, as it forms no part of my invention. Any desired form of cutter may be employed.

My improved stabber can be attached to the clamp of any of the well-known forms of paper-cutting machines, and when not needed can easily be removed therefrom. The adjustable needles will also be found to be of great advantage, as they can be adjusted to suit the size of the work being done.

Having thus fully described my invention, what I claim as new, and desire to secure by Letters Patent, is—

1. A stabbing attachment for paper-cutting machines, comprising a bar having stabbing-needles attached to its under side and provided with means for attaching it to the under side of the clamp of the cutter, substantially as shown and described.

2. A stabbing attachment for paper-cutting machines, comprising a bar having adjustable

stabbing-needles attached to its under side and provided with means for attaching said bar to the under side of the clamp of the cutter, substantially as shown and described.

5 3. A stabbing attachment for paper-cutting machines, comprising a bar having a longitudinal recess on its under side, adjustable blocks mounted in said recess and carrying stabbing-needles on their under sides, and
10 means for attaching said bar to the under side of the clamp of the cutter, substantially as shown and described.

4. A stabbing attachment for paper-cutting machines, comprising a bar having a longitudinal recess on its under side, adjustable blocks mounted in said recess and having spring ends and carrying stabbing-needles on their under sides, and means for attaching the bar to the under side of the clamp of the cutter, substantially as shown and described.

5. A stabbing attachment for paper-cutting machines, comprising a bar having a longitudinal recess on its under side, a central fixed stabbing-needle attached to said bar, 25 adjustable blocks mounted in the longitudinal recess on each side of said fixed needle and carrying stabbing-needles on their under sides, and means for attaching the bar to the under side of the clamp of the cutter, substantially as shown and described.

6. A stabbing attachment for paper-cutting machines, comprising a bar having a longitudinal recess on its under side, adjustable blocks mounted in said recess and carrying 35 stabbing-needles on their under sides, a curved arm secured to said bar and extending up over the top of the same, and a set-screw mounted in the end of said arm, substantially as shown and described, whereby 40 the bar may be attached to the clamp of the cutter.

7. A stabbing attachment for paper-cutting machines, comprising a bar having a longitudinal recess in its under side, adjustable 45 blocks having spring ends and mounted in said recess and carrying stabbing-needles on their under sides, a curved arm secured to

said bar and extending up over the top of the same, and a set-screw mounted in the end of said arm, substantially as shown and described, whereby the bar may be attached to the clamp of the cutter by said set-screw.

8. The combination, with the clamp of a paper-cutting machine provided with a longitudinal flange on its rear side, of a bar having a longitudinal recess on its under side, adjustable blocks mounted in said recess and carrying stabbing-needles on their under sides, an upwardly-curved arm secured to the bar and extending up over the same, and a set-screw mounted in the end of said arm and adapted to engage the flange of the clamp to secure the bar to said clamp, substantially as shown and described.

9. A stabbing attachment for paper-cutting machines, comprising a bar, blocks secured to the under side of said bar and adjustable longitudinally thereon, stabbing-needles attached to the under side of said blocks, and means for attaching the bar to the under side 70 of the clamp of the cutter, substantially as shown and described.

10. A stabbing attachment for paper-cutting machines, comprising a bar having stabbing-needles attached to its under side, an arm secured to said bar and extending up over the top of the same, and a set-screw mounted in said arm, substantially as shown and described, whereby the bar may be attached to the under side of the clamp of the cutter.

11. A stabbing attachment for paper-cutting machines, comprising a bar, adjustable stabbing-needles attached to its under side, an arm secured to said bar and extending up over the top of the same, and a set-screw 85 mounted in said arm, substantially as shown and described, whereby the bar may be attached to the clamp of the cutter.

In testimony whereof I affix my signature in presence of two witnesses.

AMBROSE C. STOUDER.
